UNITED STATES PATENT OFFICE.

LAURENCE E. TOPHAM, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

FEEDING MECHANISM FOR SEWING-MACHINES.

1,170,023.

Specification of Letters Patent.

Patented Feb. 1, 1916.

Original application filed April 15, 1911, Serial No. 621,286. Divided and this application filed May 10, 1915. Serial No. 27,078.

To all whom it may concern:

Be it known that I, LAURENCE E. TOPHAM, a citizen of the United States, residing at Swampscott, in the county of Essex and State of Massachusetts, have invented certain new and useful Improvements in Feeding Mechanism for Sewing-Machines; and I do hereby declare the following to be a full, clear, and exact description of the invention, such as will enable others skilled in the art to which it appertains to make and use the same.

The present invention relates to feeding mechanism for sewing machines.

15 The object of the present invention is to produce a feeding mechanism of improved construction suitable for use in high speed sewing machines and particularly adapted for use in wax thread sewing machines in 20 which the work is fed by the awl or the needle although also capable of use in other types of sewing machines.

With this object in view the present invention consists in the constructions, combinations and arrangements of parts herein-after described and claimed, the advantages of which will be obvious to those skilled in the art from the following description.

The present application is a division of 30 application Ser. No. 621,286, filed April 15, 1911, which fully illustrates and describes a wax thread lockstitch sewing machine employing a straight awl and a straight hook needle. In the drawings accompanying the

35 present application only so much of this sewing machine is illustrated as is necessary to enable the construction and mode of operation of the work feeding mechanism to be understood.

40 Referring to the drawings; Figure 1 is a view in front elevation of the machine; Fig. 2 is a vertical sectional view of the machine looking toward the rear and showing particularly the mechanism for actuating the 45 rock shaft of the feeding mechanism; Fig. 3 is a detail sectional plan view showing particularly the awl bar, the awl bar carrier, and the manner in which these parts are supported; Fig. 4 is a detail sectional 50 plan view illustrating particularly the rock shaft of the feed mechanism and the connections therefrom to the awl bar carrier; Fig. 5 is a detail sectional plan view taken on the line 5 of Fig. 2; Fig. 6 is a detail view

showing the spiral rib for the micrometer adjustment of the awl feed; and Fig. 7 is a vertical sectional view of the machine looking toward the rear and showing particularly the mechanism for actuating the rock shaft from which the awl is reciprocated.

The work to be sewn is supported in the machine by means of a flat work support formed by the throat plate 1 which is provided with the usual slot through which the needle and awl operate.

The presser foot 2 which co-operates with the work support to position the work is of usual construction, and is secured to the lower end of a presser bar 3. During the greater part of the cycle of operations of the machine the presser foot is held against the work by the pressure of a comparatively heavy spring, so that the work is tightly clamped between the presser foot and work support. During the feeding movement of the work, however, the presser foot is raised from the work so as to offer no resistance to the feeding movement. At the end of the feeding movement the presser foot is released and is again pressed against the work by said spring so that it has an opportunity to accommodate itself to the thickness of the stock. The presser foot remains pressed against the work until the beginning of the next feeding movement, when it is again lifted and the cycle of operations repeated, all as fully described in the application above referred to.

The work is fed through the machine from right to left by means of a straight awl indicated at 52. The awl is secured by means of clamping screw 53 in a socket formed in the lower end of a vertically reciprocating awl carrier or bar 54. The awl bar 54 is slidably mounted in a box or carrier 55 which is hung from the machine frame and is maintained in vertical alinement therewith by means of an arm 56 and twin lever arms 57 and 58 which are parallel to the arm 56. The lever arms 57 and 58 are power oscillated to impart a lateral swinging movement to the carrier 55 and the arm 56 acts as a link to co-operate therewith in maintaining the alinement of the carrier. The arm 56 projects from a rock shaft 59 which is free to turn upon pivot pins 60 and 61 mounted on the machine frame and is pivotally connected at 62 to the upper end

2 of the carrier 55. The twin lever arms 57 and 58 which move the carrier 55 are formed integrally with a power oscillated rock shaft 63 and are pivotally connected to the carrier 55 by means of journaled bearings upon the pivot pins 64 and 65 which are clamped in the front and rear ends respectively of an elongated sleeve 66 formed integrally with the carrier 55. The two somewhat separated 10 bearings of the arms 57 and 58 upon the carrier 55 maintain said carrier from turning about a vertical axis. The rock shaft 63 is mounted at its front and rear ends upon pivot pins 67 and 68 respectively secured to the machine frame. The rock shaft 63 has rigidly clamped upon it near its rear end, a sleeve 69 formed with radially extending twin arms 70. The ends of the arms 70 are journaled upon projecting pins 71, which are clamped in a sleeve 72 formed on the lower end of a cam actuated swinging bar 73 which oscillates the rock shaft 63, the two separated bearings of the pins 71 serving to maintain the bar 73 from turning 15 about its longitudinal axis. The bar 73 is actuated by a cam roller 74 which is carried upon the upper end of said bar and which runs in a cam path cut in the rear face of the cam wheel 75 mounted on the forward 20 end of the main driving shaft 29. The timing of this cam path is such that the feeding movement takes place while the awl is in the work. The bar 73 is hung from a fixed pivot 76 by means of a link 77 which is 25 pivotally secured to the bar 73 at 78. The pivotal connection 78 between the bar 73 and link 76 acts as a swinging fulcrum for the bar and is constrained to swing in the arc of a circle about the fixed pivot 76. 30 The swinging fulcrum 78 allows the bar 73 to act in the combined capacity of a lever and a link, the pivotal connection 78 allowing the bar 73 to oscillate about it as a lever, while the link 77 allows the bar 73 to act as 35 a link in transmitting the component of its movement in the direction of the arc of swing of the pivotal point 78 about the fixed pivot 76. The other constraints on the bar 73 are the engagement of the cam roller 74 40 in the cam wheel 75 which actuates said bar, and the connection of the lower end of said bar to the rock arms 70 to which it imparts its motion to actuate the awl feed. It will be evident that if the position of the fixed 45 pivot 76 be adjusted, the consequent change in the arc of movement of the swinging fulcrum 78 will change the resultant movement imparted to the rock arms 70 and will therefore change the length of the lateral feeding 50 movement of the awl. With this object in view the fixed pivot 76 is carried upon the end of an arm 79 extending radially from the forward end of a shaft 80 which is journaled in a bracket 81 formed on the inside 55 of the machine frame and which is arranged

to be manually turned to adjust the position of the fixed pivot 76. The arm 79 and the link 77 are equal in length and the parts are so proportioned that when the bar 73 is raised to its highest position, the swinging fulcrum 78 will be coaxial with the shaft 80. The position of the awl at the completion of its feeding movement corresponds to the raised position of the bar 73 and it is evident, since the swinging fulcrum 78 and shaft 80 are co-axial, that the turning of the shaft 80 to adjust the position of the point 76 will not affect this position of the awl. When, however, the bar 73 is moved downwardly by the action of its driving cam, the 80 swinging fulcrum 78 is swung from its co-axial position with respect to the shaft 80 and the amount of turning which it imparts to the rock arms 70 at the downward limit of its movement will depend upon the position of the fixed pivot 76. The position of the awl at the beginning of its feed stroke corresponds to the downward position of the bar 73 and consequently this position of the awl will be varied by the manual adjustment 90 of the position of the pivot 76. The awl will thus always be brought to the same position at the completion of its feeding movement when it is withdrawn from the work for the entry of the needle into the awl hole, but the awl will have its position when it enters the work at the beginning of its feeding movement varied laterally to produce the desired length of feed.

The shaft 80 is arranged to be manually 100 turned to adjust the position of the pivot 76 by means of an arm 82 secured to the rear end of said shaft and extending outwardly through an aperture 83 in the side of the machine frame. The end of the arm 82 is 105 cylindrical in cross section, and is forwardly offset from and somewhat inclined to the main portion of said arm. This inclined end portion of the arm 82 is provided with a longitudinally extending recess 84 for the 110 reception of a cylindrical plunger 85. The face of the projecting end of this plunger is formed with a spiral rib 86 to engage a fixed segmental toothed plate 87 to hold the arm 82 in an adjusted relation thereto. The 115 plunger 85 is normally held against the toothed plate 87 by means of a helical compression spring 88, and is adapted to be either retracted against the spring or to be rotated by means of a knurled cap 89 which 120 is secured to the projecting end of the reduced plunger shaft or pin 90. A coarse adjustment of the awl feed is had by retracting the plunger 85 and turning the arm 82 with relation to the toothed plate 87, and a fine or micrometer adjustment is had by rotating the plunger 85 which will cause the spiral rib 86 to carry the arm 82 slowly along the toothed plate 87.

The mechanism for reciprocating the awl, 130

while permitting it to move laterally to feed the work, comprises a link 91, the lower end of which is pivotally secured at 92 to the slidably mounted awl bar 54 and the 5 upper end of which is pivotally secured at 93 to the end of an arm 94 projecting radially from the forward end of an oscillating rock shaft 95 journaled in the machine frame. The rock shaft 95 is oscillated by 10 means of a reciprocating link 96, one end of which is pivotally secured at 97 to an arm 98 projecting radially from the rear end of said rock shaft. The other end of the link 96 is journaled upon a crank pin 99 carried 15 upon the front face of the cam wheel 75 which is mounted upon and continuously rotated by the main driving shaft 29. The rock shaft 95 and its two arms 94 and 98 act as an intermediate pivoted lever between the 20 awl bar and the continuously rotating crank, the arms 94 and 98 being the power delivering and receiving arms respectively and the axis of the rock shaft 95 being the fulcrum. When the awl is at the lower or forward 25 limit of its stroke the connecting point 93 is carried somewhat to the right of the position which it occupies as a dead center when the points 92 and 93 and the axis of the rock shaft 95 are in alinement. The movement 30 of the point 93 to the right beyond its position as a dead center imparts a slight retractive movement or idle backward and forward movement to the awl at the limit of its downward or forward stroke. This 35 slight retractive movement of the awl tends to lift the work slightly from the work support so that the awl may more easily carry the work to the left during its feeding movement which takes place after the awl 40 has penetrated the work. The awl is moved comparatively rapidly as it passes through the work, so that as little time as possible is consumed by the awl in puncturing and withdrawing from the work, and the awl 45 bar carrier 55 is long enough to permit the back stroke of the awl to be lengthened to consume approximately 220° of a revolution of the driving shaft between the time that the awl leaves and enters the work.

50 The invention having thus been described, what is claimed is:—

1. A sewing machine, having in combination, stitch forming devices, a work feeding device, mechanism for imparting feed and 55 return movements to said device comprising a longitudinally moving and oscillating bar, connections between said bar and the feeding device for directly transmitting the longitudinal and oscillating movements of the 60 bar to the device, a supporting link hung from a fixed pivot at one end and pivotally connected at the other end to said bar to form a swinging fulcrum therefor, power driven means connected to and adapted to 65 move said bar to turn it about its swinging

fulcrum and to turn said link about its fixed pivot, and means for adjusting the position of the fixed pivot of the supporting link to vary the amount of movement imparted by said bar to the feeding device. 70

2. A sewing machine, having in combination, stitch forming devices, a work feeding device, mechanism for imparting feed and return movements to said device comprising a longitudinally moving and oscillating bar, 75 connections between said bar and the feeding device for directly transmitting the longitudinal and oscillating movements of the bar to the device, a supporting link hung from a fixed pivot and pivotally connected 80 to said bar to form a swinging fulcrum therefor, a cam connected to and adapted to turn said bar as a lever about its swinging fulcrum and to thrust said bar as a link in the direction of movement of the swinging 85 fulcrum about the fixed pivot, and means for adjusting the position of the fixed pivot to vary the path of movement of the swinging fulcrum whereby the amount of movement imparted to the feed device may be 90 varied.

3. A sewing machine, having in combination, stitch forming devices, a work feeding device, mechanism for imparting feed and return movements to said device comprising 95 a longitudinally moving and oscillating bar, connections between said bar and the feeding device for directly transmitting the longitudinal and oscillating movements of the bar to the device, a supporting link having 100 one end connected to said bar to form a swinging fulcrum therefor, an arm pivotally mounted on the machine frame to which the other end of said link is connected, power driven means for moving said bar 105 to actuate the feeding device, said means being arranged to move the swinging fulcrum of the bar into a position co-axial with the pivotal mounting of said arm at one extremity of the movement of the bar, and 110 means for adjusting said arm in its pivotal mounting.

4. A sewing machine, having in combination, stitch forming devices, a work feeding device, mechanism for imparting feed and return movements to said feeding device comprising a longitudinally moving and oscillating bar, connections between the bar and the feeding device for directly transmitting the longitudinal and oscillating movements of 120 the bar to the device, an arm pivotally mounted on the machine frame, a link equal in length to the arm, one end of which is pivotally hung from the free end of the arm and the other end of which is connected to 125 and forms a swinging fulcrum for the bar, power driven means for moving the bar to actuate the feeding device, said means being arranged to move the bar so that its swinging fulcrum is co-axial with the pivotal 130

mounting of the arm at the completion of the work feeding movement, and means for adjusting said arm in its pivotal mounting whereby the arc of movement of the swinging fulcrum may be varied to vary the amount of movement imparted to the work feeding device.

5. A sewing machine, having in combination, stitch forming devices, a work feeding device, mechanism for imparting feed and return movements to said feeding device comprising a longitudinally moving and oscillating bar, connections between the bar and feeding device for directly transmitting the 10 longitudinal and oscillating movements of the bar to the device, power driven means for moving the bar to actuate the feeding device, a supporting link, one end of which is connected to said bar and forms a swinging fulcrum therefor, a shaft journaled in the machine frame, an arm carried by said shaft from the free end of which the supporting link is hung, a second arm carried by said shaft, manually operable means carried upon the free end of the said second arm to turn the arm and lock it in adjusted position whereby the free end of the first arm from which the link is hung may be 15 adjusted in position to vary the amount of movement of the feeding device.

20 6. A sewing machine, having in combination, stitch forming devices, a work feeding device, power driven mechanism connected to and imparting feed and return movements to said device, and means for making a gross and a fine adjustment of said power driven mechanism to vary the amount of movement of the work feeding device, said

means comprising a manually adjustable device operating to make a gross adjustment independently of the fine adjustment, and a device for making a fine adjustment of said manually adjustable device in any of its adjusted positions.

7. A sewing machine, having in combination, stitch forming devices, a work feeding device, power driven mechanism connected to and imparting feed and return movements to said feeding device, and manually adjustable means for varying the amount of movement imparted to the feeding device comprising a fixed toothed plate, a member movable relatively thereto, and a rotatable worm mounted in said member and meshing with said toothed plate.

8. A sewing machine, having in combination, stitch forming devices, a work feeding device, power driven mechanism connected to and imparting feed and return movements to said feeding device, manually adjustable means for varying the amount of movement imparted to the feeding device comprising a fixed toothed plate, a member movable relatively thereto, a plunger rotatably and slidably carried in said member and having a worm to engage with the toothed plate, a spring normally pressing the plunger against the toothed plate, and means for withdrawing the plunger from the toothed plate and moving said member relatively thereto to provide a gross adjustment and for turning said plunger to cause the worm to slowly move said member relatively to the toothed plate to provide a micrometer adjustment.
